UNITED STATES PATENT OFFICE.

CABLE B. JONES, OF WHITEWOOD, SOUTH DAKOTA.

DERRICK.

1,090,067.

Specification of Letters Patent. Patented Mar. 10, 1914.

Application filed October 26, 1912. Serial No. 727,863.

To all whom it may concern:

Be it known that I, CABLE B. JONES, a citizen of the United States, residing at Whitewood, in the county of Lawrence, State 5 of South Dakota, have invented certain new and useful Improvements in Derricks; and I do hereby declare the following to be a full, clear, and exact description of the invention, such as will enable others skilled in 10 the art to which it appertains to make and use the same.

This invention relates to derricks and the object of the invention is to provide a derrick having pivotal beams provided with 15 means for adjustably securing their free ends to the derrick platform, these beams being equipped with sheaves for the reception of the derrick cable, the beams being shifted relatively to each other to space the cable 20 sheaves any desired distance apart whereby to vary the swinging action of the cables on the derrick boom.

With the above object in view, the invention consists of certain novel details of construction and combination of parts herein- 25 after fully described and claimed, it being understood that various modifications may be made in the minor details of construction within the scope of the appended claim.

30 In the accompanying drawings forming part of this specification:—Figure 1 is a side elevation of the derrick. Fig. 2 is a front elevation of the derrick. Fig. 3 is a horizontal sectional view taken on the line 35 3—3 Fig. 1. Fig. 4 is a vertical sectional view taken on the line 4—4 Fig. 2. Fig. 5 is a detail front elevation of the means for connecting together the upper ends of the uprights. Fig. 6 is a side elevation of the 40 parts shown in Fig. 5. Fig. 7 is a plan view of the parts shown in Fig. 5. Fig. 8 is a cross sectional view taken on the line 8—8 Fig. 5.

45 Referring now to the drawings in which like characters of reference designate similar parts, the derrick comprises a substantially rectangular bed frame formed of longitudinal timbers 10 connected at the ends by cross timbers 11, the longitudinal timbers 50 being extended at the rear ends beyond the adjacent cross timber and being provided with bearing boxes 12 to journal the ends of a wheeled axle 13.

55 Preferably four convergent uprights 14, 15, 16 and 17 are fixedly secured at their lower ends to the bed frame and have their

meeting upper ends fixedly secured together, there being an inverted U-shaped strap 18 placed astride of the top and outer edges of the uprights 14 and 15, and a second inverted U-shaped strap 19 placed between the confronting inner edges of the said uprights, the legs of both straps being fixedly secured together and to the uprights by bolts 20. An inverted U-shaped strap 21 is arranged 65 on the rear faces of the said uprights and secured in position by bolts 22 passed through the uprights. A U-shaped strap 23 is inserted between the upper ends of the uprights 14 and 15 with the legs bearing 70 upon the bights of the upper strap 18 and lower strap 19, a bolt 24 being passed vertically through the intersections of the straps 18, 19 and 23. The strap 23 performs the function of a brace to prevent bulging of the 75 straps 18 and 19 and furthermore forms means of attachment for the uprights 16 and 17, the latter being equipped with L-shaped straps 25 and 26 respectively, these straps being bolted as shown at 27 to the 80 uprights and being provided in their free ends with registering openings to receive the bolt 24. The bolt 24 is equipped with a nut 27, and is equipped below the nut with a cotter pin 28 which positively prevents es- 85 cape of the nut.

A swinging boom 29 is secured at the lower end to the bed frame, through the instrumentality of a turning head 30 comprising a stem 31 which is swivelly mounted 90 in the transverse timber 11 at the rear end of the frame, there being spaced lips 32 formed integral with the stem and receiving therebetween the lower end of the boom, a pin 33 being passed through the lips and 95 through the boom to secure the parts together. For securing the boom in operative position a cable 34 is connected at the outer end to the upper end of the boom and is equipped at the inner end with a hook 35. 100 A pin 36 is secured vertically to the legs of the brace bracket 23 and is equipped with a clevis 37 which interlocks with the hook 35. Chains 38 are secured respectively to the uprights 14 and 15 and to the cable 34. 105 These chains limiting swinging movement of the boom in either direction.

Secured to the longitudinal timbers 10 is a cross timber 39 upon which and the adjacent cross timber 11 of the frame a platform 40 is disposed. A pair of divergent beams 41 and 42 are pivoted at the rear ends 110

to the platform through the instrumentality of pivot bolts 43, and are equipped at the forward ends with J-bolts 44 which are passed through slots 44' in the beams and are 5 designed to hook underneath the cross timber 11, there being clamping levers 45 threaded on to the upper ends of the J-bolts, rotation of these handles serving to advance the bills of the J-bolts into the underneath 10 face of the cross timber 11 and adjustably secure the beams in any position of their swinging movements.

The swinging beam 41 is equipped with a sheave 47, and the swinging beam 42 is 15 equipped with a sheave 46. A boom swinging cable 48 is trained over the sheave 46 and is led upwardly along the boom, thence over a sheave 48' at the top of the boom, thence downward and terminally connected 20 to the power drum of a hay grapple 49', after being wrapped a few turns about the latter. A cable 49 is trained over the sheave 47 and led upwardly along the boom, being thence led through a sheave 50 carried at 25 the upper end of the boom and is then terminally connected to the hay grapple. By means of shifting the swinging beams relatively to each other, the cable carrying sheaves 46 and 47 may be placed apart at 30 any desired distance to accommodate the device to different conditions of service, as will presently appear.

In operation the boom is swung by shifting the weight of the grapple from one 35 cable to the other, and it is thought that this explanation will suffice without more extended description.

For preventing twisting of the cables together due to the grapple rotating, a weight- 40 ed cable 51 is attached to the grapple and trained over a sheave 52 carried by the boom, this cable normally holding the grapple against any tendency to rotate during swing- ing of the boom.

By means of adjusting the swinging 45 beams 41 and 42 so as to dispose the sheaves 46 and 47 at various distances from the boom, the speed of the boom may be regulated, since by spreading the beams apart the sheaves will be spaced a considerable dis- 50 tance from the boom, and, consequently, the speed of the boom increased, while by clos- ing the beams toward each other the sheaves will be disposed near the boom and conse- 55 quently the speed of the latter lessened. 55 When the wind is blowing against one side of the boom, the related beam must be spaced a greater distance from the boom than the opposite beam in order to facilitate the boom swinging against the wind at the same 60 speed it swings with the wind.

What is claimed, is:—

A derrick including a support, a mast thereon, a swinging boom carried by said support and suspended at the free end from 65 said mast, a pair of divergent beams piv- otally connected at their nearest ends to said support with said boom between said beams, means for adjustably securing the free ends of said beams to said support, 70 sheaves carried by the free ends of said beams, sheaves carried by the outer end of said boom, a pair of cables trained through respective sheaves on said beams and on said boom, and a load handling device oper- atively connected to said cables, shifting of the load from one to the other of said cables serving to swing said boom, an adjustment of said beams independently of each other and toward or away from said boom serving 75 80 to vary the speed of swinging movement of said boom.

In testimony whereof, I affix my signature, in the presence of two witnesses.

CABLE B. JONES.
